UNITED STATES PATENT OFFICE.

SAMUEL SIEGEL, OF NEW YORK, N. Y., ASSIGNOR TO ANNA SIEGEL, OF NEW YORK, N. Y.

METALLOPHONE.

1,291,202.

Specification of Letters Patent. Patented Jan. 14, 1919.

Application filed February 26, 1917. Serial No. 150,940.

To all whom it may concern:

Be it known that I, SAMUEL SIEGEL, a citizen of the United States, residing at New York city, in the county and State of New York, have invented new and useful 5 Improvements in Metallophones, of which the following is a full, clear, and exact description.

My invention relates to what is known to 10 the trade as metallophones, which consists principally of a series of graduated metal bars arranged so as to produce the notes of the common musical scale when struck in succession.

15 The object of my invention is to identify these metallic bars of the instrument by means of pictures or animals, or other objects, which can be easily recognized by children who can reproduce simple melodies by 20 striking the bars indicated by the pictures of the same objects arranged one after another upon a chart used in connection with my improvements. This I accomplish by the means hereinafter fully described, and 25 as particularly pointed out in the claims.

In the drawings:

Figure 1 is a plan view of my invention showing one of the charts mounted thereon.

Fig. 2 is a front edge view of the same.

30 Fig. 3 is a transverse section taken on dotted line 3—3, Fig. 1.

Referring to the drawings, 10 represents a supporting board the front edge of which is, preferably, slightly oblique to the rear 35 edge and which is supported by transverse cleats, 11, secured to the underside thereof near each end, which latter have felt pads 12 cemented or otherwise secured to the underside of their ends.

40 The supporting board has a longitudinally elongated slot 13 which extends from near one end to near the other end thereof and is situated nearer the front edge than the rear edge thereof, and this slot is narrower at its right hand end than at its left hand end and has strips of felt 14, mounted upon and suitably secured to the margins of its longitudinal edges that extend practically from end to end of the slot.

45 The metal sounding-bars 15, are arranged transversely and bridge across slot 13, and they rest upon the felt strips 14, and have holes through them that are situated near their ends down through which pegs or pins 50 16, are driven into the supporting-board to retain them in their relative positions.

These bars are arranged parallel to each other at a suitable distance apart, and the plate at the left hand end of the series is the longest and the remaining bars of said 60 series gradually decrease in length from the left hand end of the slot to the right hand end thereof where the right hand end bar is the shortest.

These bars when struck in succession from 65 left to right will reproduce the musical notes of the diatonic scale, although, if desired, an additional bar may be interposed in proper position to reproduce the sharp or flat of any of said musical notes. Between 70 the rear edge of each of said bars and the rear edge of the supporting-board, a picture of an animal or other familiar object, which can be readily recognized by the child mind, is pasted or otherwise secured to said supporting-board in alinement with bar 15 in front of it. For instance, reading from left to right the following pictures are used to identify the plates arranged in front of them, to-wit: a giraffe, an elephant, a lion, a 75 tiger, a monkey, a deer, a cow, a cat, a dog, a rabbit, a horse and a hen.

These pictures are, preferably, printed upon strips of paper, but it is obvious that the representation of the animals, named, 80 or the pictures of such other objects as may be substituted therefor, may be embossed or in intaglio or otherwise made, as, obviously, it would not involve invention to employ any of these methods of illustration. 85 If the pictures are printed on paper the subject of each of said pictures may be identified by printing the name thereof immediately above the pictures, as shown, and, if desired, the note produced by striking the 90 bar indicated by each picture can be identified by the proper musical character properly disposed in the lines and spaces of the musical staff, 17.

When this musical notation is employed, 100 I prefer to place the name of the musical note produced by the bar above it, and place the letter indicated by said musical character above the same. Thus, the bar at the left hand end of the series of sounding-bars is 105 identified by the picture of a giraffe. The word "Giraffe" is printed above the said picture, a quarter note is shown on the line below the musical staff above the word "Giraffe" and the letter "C" is printed 110 above the musical staff.

The chart 18 used in connection with my

invention is the same as that described in Letters Patent of the United States granted to me October 17, 1916, No. 1,201,769, for toy piano, and which near its upper edge has several bars of musical characters properly disposed on a staff that compose a simple melody and then has several horizontally disposed series of pictures corresponding to pictures 19 mounted on the supporting-board that are arranged one after the other so that by striking with a suitable hammer the bars indicated by the corresponding pictures, in the order in which they are arranged, the melody readable on the musical staff above them can be produced. This chart 18 is, preferably, printed on stiff card board, and it is held in position where it can be easily read by the musician by inserting its lower edge in a longitudinal groove extending, preferably, from one end of the supporting-board to the other near the rear edge and inclined slightly so as to tilt the chart rearwardly.

What I claim as new is:

1. A musical instrument comprising a supporting-board, a sounding bar mounted thereon and extending longitudinally away from the forward edge of the board, and means for identifying the note given out by said bar comprising, in substantial alinement with the bar and disposed rearwardly

thereof in the following order, the picture of a familiar object, the name of such object, the musical indication of the said note and the letter of the diatonic scale corresponding to said note. 31

2. A musical instrument, comprising a supporting-board, a sounding-bar mounted thereon and extending longitudinally away from the forward edge of the board, and 41 arbitrary and musical indicia for identifying the note given out by said bar, said indicia being alined with the bar and disposed rearwardly thereof.

3. A musical instrument, comprising a 41 supporting-board, a musically graduated set of sounding bars mounted thereon each extending longitudinally away from the forward edge of the board, and arbitrary and musical indicia for each bar positioned rearwardly of and in alinement with the bar; said arbitrary indicia for the bars being in transverse alinement across the board and the musical indicia being similarly transversely alined. 51

In witness whereof I have hereunto set my hand this 3d day of February, 1917.

SAMUEL SIEGEL.
